Specification for Design.

Patented June 7, 1921.

Application filed October 29, 1920. Serial No. 420,564. Term of patent 7 years.

To all whom it may concern:

Be it known that I, WILLIAM J. GRADY, a citizen of the United States, residing at Decatur, in the county of Macon and State of Illinois, have invented a new, original, and ornamental Design for an Arm for a Portable Lighting-Fixture, of which the following is a specification, reference being had to the accompanying drawing, forming a part thereof.

Figure 1 is a side elevation of an arm for a portable lighting fixture, showing my new design.

Fig. 2 is a front elevation of the same.

I claim:

The ornamental design for an arm for a portable lighting fixture, as shown.

WILLIAM J. GRADY.
